DESIGN FOR A WOMAN'S TROUSERED GARMENT

Irma Praet, Detroit, Mich.

Application March 4, 1935, Serial No. 55,705

Term of patent 14 years

To all whom it may concern:

Be it known that I, Irma Praet, a citizen of Belgium, residing at Detroit, in the county of Wayne and State of Michigan, have invented a new, original, and ornamental Design for a Woman's Trousered Garment, of which the following is a specification, reference being had to the accompanying drawing, forming part thereof, wherein:

Fig. 1 is a front view of a woman's trousered garment embodying the new design.

Fig. 2 is a rear view thereof.

I claim:

The ornamental design for a woman's trousered garment as shown.

IRMA PRAET.
